US0D1029829S

(12) **United States Design Patent** (10) **Patent No.:** **US D1,029,829 S**
(45) **Date of Patent:** **** Jun. 4, 2024**

(54) **ATTACHMENT FOR ELECTRONIC DEVICE**

(71) Applicant: **Wacom Co., Ltd.**, Kazo (JP)

(72) Inventor: **Naoya Nishizawa**, Toyko (JP)

(73) Assignee: **Wacom Co., Ltd.**, Kazo (JP)

(**) Term: **15 Years**

(21) Appl. No.: **29/819,587**

(22) Filed: **Dec. 16, 2021**

(30) **Foreign Application Priority Data**

Jun. 24, 2021 (JP) ..... 2021-013732 D

(51) **LOC (14) Cl.** **14-02**

(52) **U.S. Cl.**

USPC **D14/356**

(58) **Field of Classification Search**

USPC ..... D14/125, 126, 127, 138, 140, 149, 171, D14/204, 209.1, 211, 215, 216, 217, 240, D14/251, 252, 253, 299, 300, 307, 314, D14/323, 345, 355, 356, 357, 358, 385, D14/389, 422, 432, 439, 434, 433, 435, D14/436, 435.1, 440, 447, 451, 452, 454, D14/457, 496; D13/102, 103, 107, 108, D13/184, 110, 118, 119, 123; D10/70 CPC G06F 1/1632; G06F 1/16; G06F 1/1688; G06F 1/1616; G06F 1/1626; G06F 1/1658; G06F 3/065; G06F 13/382; G06F 13/385; G06F 13/387; G07G 1/0018; G07G 1/12; H01M 10/44; H01M 10/46; H01M 10/425; H03M 11/00; H01H 13/14; H01H 13/84

(57) **CLAIM**

The ornamental design for an attachment for electronic device, as shown and described.

DESCRIPTION

FIG. 1 is a top-front-right perspective view of an attachment for electronic device according to an embodiment of my new design;

FIG. 2 is a bottom-front-right perspective view thereof;

FIG. 3 is a top-rear-right perspective view thereof;

FIG. 4 is a bottom-rear-left perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is top plan view thereof; and,

FIG. 10 is a bottom plan view thereof.

The broken lines in the figures depict portions of the attachment for electronic device that form no part of the claimed design.

1 Claim, 8 Drawing Sheets
